BOTTLE WASHING MACHINE

Paul E. Fletcher, Harrisonburg, Va.

Application August 1, 1931, Serial No. 554,553

3 Claims. (Cl. 15—61)

My invention relates to an improvement in machines for sterilizing and cleansing bottles by successively soaking them in hot chemical solution, brushing and cleansing them externally, brushing and cleansing them internally, and finally rinsing them, the objects of my invention being to provide a simple, automatic means of doing this, with fewer working parts than in previous machines, with the working parts more accessible, and therefore having the advantage of being less expensive to manufacture and operate and more positive in operation than the complicated machines that have preceded it.

These and other objects and advantages of my improved machine will be apparent in the course of the following description, as well as in the drawings, in which—

Figure 1 is a diagrammatic part sectional side elevational view showing in detail the various mechanical details comprising my invention.

Figure 2 is a side view in elevation of the side adverse to that shown in Figure 1, clearly illustrating certain features of my invention, herein-after explained in detail.

Figure 3 is a partial rear end elevational view of my machine, with tank door removed, illustrating the shaft and cam elements comprised in my invention.

Figure 4 is an enlarged fragmentary detailed view of the shaft and cams arrangement shown in Figures 1 and 3.

My improved automatic machine for washing bottles, shown in the aforementioned drawings comprises in general a main frame, an endless series of bottle carriers transportable along a definite course within said frame by means of conveyor chains, actuating means for said chains, and a loading and unloading conveyor and table with means for automatically feeding bottles into and ejecting them from the bottle carriers and machine.

As the bottles in the carriers are carried through the machine they are automatically immersed and soaked in a tank section of the machine containing hot chemical solution, inverted to drain such solution therefrom, and each carrier of bottles then successively rinsed and brushed externally, rinsed internally, brushed internally, and again rinsed internally, by means provided in the machine. Following these operations, the bottles are drained of the rinsing liquid, and carried forward to the ejecting means above referred to.

All of these various operations and mechanism are synchronized to operate in such a manner that while the conveyor chain is stationary, being moved intermittently, the bottles in the most advanced carrier are ejected from the machine, and another carrier is filled, immediately followed by the soaking, draining, brushing, and rinsing operations. These operations being completed,

the mechanical brushing and rinsing ceases, the operating means are withdrawn from the bottles and placed in a position of noninterference with subsequent movements of the machine, and the carriers are advanced so that each operation may be repeated with the next following carrier full of bottles.

My invention comprises the essential means, in combination, of accomplishing the foregoing which I will now explain in detail, reference being made to the accompanying drawings.

Figures 1, 2, 3, and 4 show the basic actuating means comprised in my invention, being a combination of levers and rocker-arms operated by a series of cams and cranks on the rotatable shaft 1 (Fig. 3) journaled in the frame of the machine. Said shaft 1 is geared to shaft 2 by peripheral gear on box cam 8 and gear on said shaft 2 (both shown in Fig. 3), said shaft 2 and pulley thereon being connected with the motor 20 in the conventional manner. This may be done by means of a corresponding pulley on shaft 39 and belt connection (as indicated by dotted lines in Fig. 2) with shaft and pulley 2.

As shown in Fig. 1, the bottles to be cleansed are carried through the machine by the usual type of carriers 3, comprising cone or pyramid shaped bottle compartments, extending transversely across the machine, and supported at each end on endless conveyor chains 4. Said chains 4 travel on rollers, in tracks secured to the frame of the machine on each side, and have a line of travel as shown in Fig. 1.

The forward movement of said endless chains 4 and carriers 3 is accomplished by an arm 5 with pawl 6 engaging each of said chains as they enter the horizontal tracks along the top of the machine after having left the track of the inclined run from the rear of the machine.

The box cam 8, roller 9 on arm 10 (Figs. 1, 3, 4) and transverse shaft 11 to which is keyed the link member 12, said link being pivoted on arm 10, impart an oscillating movement to the links 7 which are keyed to the shaft 11 on each end thereof and in line with the conveyor chains 4 so that by their pivotal connection with the pawl arms 5 said pawl arms are kept in line with said chains. When actuated forward by the rotation of the box cam 8, and the oscillation of the shaft 11, the pawls 6 engage the chains 4 and advance them with their appended bottle carriers concurrently. The distance of such advance is regulated by the size of the cam 8 and connecting arms and levers in such manner that when the movement ceases and the pawls 6 are returned to operating position the carriers have been advanced one position, and each is therefore ready for the succeeding operation.

Figs. 1 to 4 show in detail the mechanism for feeding the bottles into the machine and eject-

ing them, comprising the peripheral cam 13 on the cam shaft 1, a crank 14 on an oscillatory shaft 15, and a roller 16 at the upper extremity of said crank 14 in contact and actuated by the 5 rotation of the peripheral cam 13. The oscillatory shaft 15 is journaled in the frame of the machine and extends through one side thereof, at which point the vertical arm 17 is rigidly attached thereto. This arm 17 is pivoted to the 10 horizontal lever 18, and as the cam shaft 1 rotates the peripheral cam 13 the horizontal lever 18 is moved toward the rear of the machine, oscillating the transverse shaft 19, journaled in the frame at the front end thereof, by connecting member 20.

Push arms, or fingers 21, are rigidly attached to said shaft 19 and its oscillating movement carries said arms, in channel slots provided in the loading table 22, toward the openings of the bottle 20 carrier automatically placed in position for loading, pushing bottles horizontally placed on said table and in said channels into said carrier.

The table 22 is pivoted in the frame of the machine at its forward end 23, and is suspended 25 at its rearward end by springs secured to the frame of the machine, and by means of a vertically extending member 24 engaging the slots in power control handle 25 acts as an automatic stop. When bottles on the loading table 22 do 30 not completely enter the carrier being loaded, for any reason, the forward end of the table is depressed by the downward movement of the carrier and bottle, and the control handle 25 released, from its position with its forward end 35 against the belt to pulley on shaft 39, and enables the belt to travel free of said pulley and shaft.

As shown in Fig. 2 crank 26 is also rigidly attached to said oscillating shaft 19, and by rod 40 27 pivoted to said crank 26 and arm 28, an oscillating movement is given to the upper transverse shaft 29 which is journaled in the frame of the machine. A plurality of arms 30, supporting bottle retainers 31 extending transversely 45 across the machine in position to receive bottles ejected from the carriers, are rigidly attached to said shaft 29, with a cooperating stationary base member 32 so placed as not to interfere with the movement of said arms and bottle retaining members.

With the forward movement of the conveyor chains and carriers the bottle compartments of one carrier, being the most advanced carrier, leave the front plate 33 (Fig. 1) and are thereby denied 55 of means holding them in the carrier. As they face the opening in the machine front, said bottles fall by gravity out of the carrier and slide over said base member 32, resting in an inclined position on the movable retainers 31. With the oscillation of the shaft 29, actuated as hereinbefore described, the retainers 31 are moved 60 upwardly in an arc by the arms 30 until the bottles held therein reach a vertical position and rest on the conveyor chain 34, from which they are taken to the filling machines.

It will be noted from Figs. 1, 2 that the conveyor chain 34 may be actuated by a shaft 35 connecting with chain drive 36, horizontal shaft 37, and vertical shaft 38, geared to the pulley 70 shaft 39 in the usual manner (Fig. 1). As an alternative, said conveyor chain may be actuated by combination with the conveyor chain of the filling machine and its actuating means.

When the concurrent ejection of clean bottles 75 from the machine, and feeding of dirty bottles,

is completed, the continued movement of the peripheral cam 13, aided by the spring 40, again returns the fingers 21 and bottle retainers 31 to their operating position.

As hereinbefore pointed out, during the 5 interval that the carriers and conveyor chains are stationary the soaking, draining, brushing and rinsing operations in the machine are taking place.

With the downward and forward movement of the carriers at the front of the machine, the bottles enter the tank 41 and are filled with hot chemical solution. The solution in the tank is heated by the usual means, viz., steam coil, gas flame, etc. and the bottles soak therein with the successive forward movement of the carriers until carried around the sprocket or wheel 42 and inverted, when the solution remaining in said bottles is drained therefrom. This drainage is returned to the tank by means of the drain pan 20 formed by the inclined side of the tank 41.

Upon emerging from the solution tank 41, the bottles are ready for the brushing and rinsing operations. This operation requires that the centering funnels 43 be placed in direct contact with the mouths and necks of the bottles to be brushed and rinsed, and that rinsing and brushing means be provided.

Figures 1 and 2 show the transverse series of centering funnels 43 raised into contact with the 30 bottles, and the rinsing means and brushes in their normal position for operation, the operation thereof being explained as follows.

The frame members 44 support cross-members extending transversely across said frame members, the centering funnels 43 being supported thereon with apertures in said cross-members under each of the centering funnels. The frame members 44 also support headers 45 which supply water for the rinsing operations by jets 46 40 placed immediately under the rinsing funnels, as shown, said headers being connected with the flexible water supply line 47.

A depending member of said frame members 44, supports transversely disposed cross-members, 45 sleeves 48 extending downwardly therefrom and upwardly through the corresponding cross-member supported by the upper member of frame 44 to the centering funnels thereon for the brushes 49, as shown, said sleeves 48 forming a casing for 50 said brushes and their stems 50.

As the forward movement of the conveyor chains 4 and carriers 3 ceases the frame 44 and all its appurtenances including the centering funnels 43, which have been lowered during the 55 movement of the carriers 3, are actuated upwardly until said funnels are in direct contact with and around the necks of the stationary bottles to be brushed and rinsed.

The frame 44 and supported attachments above 60 referred to, is arranged to slide vertically in a groove between the uprights 51 on each side of the machine, being actuated by a rocker arm 52 on each end pivoted to the frame supporting member 53. The rocker arms 52 are keyed to the shaft 65 54 extending transversely across the machine and journaled in the frame thereof, and are also connected by a similar transverse shaft 55 at the extreme rear end thereof, the latter shaft being vertically movable in a slot 56 in each side of the machine. Supports 57 depend from said shaft 55 inside the machine and are jointly pivoted on the lever 58, the opposite (or forward) end of said lever being keyed to the shaft 54 in manner similar to the rocker arms 52 (see Fig. 1). 70 75

The lever 58 (Figs. 1, 3) is actuated by the roller 59 (Fig. 4) thereon, said roller being fixed in the groove of the box cam 60 (Figs. 3, 4) which, by actuating downwardly the lever 58, and consequent oscillation of the shaft 54, raises the forward end of the rocker arms 52, and actuates the frame 44, centering funnels 43, headers 45, and jets 46 upwardly to the position shown in Figs. 1 and 2.

As the movement of the cam 60 continues the rear ends of the lever 58 and rocker arms 52 are forced upwardly, and by the reverse of the movements above described the funnels, jets, etc. are lowered from the bottles to allow their further movement with the carriers.

It is to be noted that the plate 61 (Figs. 1-2), which is lowered during the brushing operation against the inverted bottles to prevent their revolving and displacement, is raised from contact with said bottles by the lowering of the centering funnels in order that the upper surface of the carrier unit will be free to move forward also. This is accomplished by a series of levers 62, 63, 64 (see Fig. 2), pivoted to the rocker arm 52 and each other in the manner shown in Figs. 1 and 2, actuating upwardly a member 65 on each side of the machine supporting said plate 61, said supporting member 65 being vertically slidable in a frame 66 and slot extending from the frame of the machine.

The rinsing and brushing operations are so timed that they follow almost immediately after the centering funnels just described have seated against the bottles.

As shown in Fig. 1, the bottles over the centering funnels 43 nearest the exit from the soaking tank 41 are raised from their carrier on spindles 67 projected through the centering funnels, and thrust vertically between the rotary brushes and a spray of the conventional type on the water supply line shown entering the chamber 68, where their exteriors are cleansed.

The next forward carrier of bottles is in contact with a column of water from jets under their centering funnels, whereby their interiors are rinsed of any of the chemical solution remaining therein.

The next two forward carriers of bottles have had inserted in them through their respective centering funnels the revolving brushes 49, causing said bottles to be thoroughly brushed internally. As this brushing operation is taking place, the plate 61 rests on the bottoms of the inverted bottles to prevent their rotation and displacement.

The last two forward carriers of bottles connected with the centering funnels are receiving a final rinsing spray of water through jets under their centering funnels to cleanse them of any substance not previously removed.

The brushes 49 rotate on their stems 50, actuated by the gears in gear box 69 (Fig. 1), which in turn are actuated in the usual manner such as by being geared and connected by a shaft 70 (Fig. 2) with gears operating from the shaft 39 (Fig. 1) in a box thereon.

The rotary brushes in the chamber 68 may be actuated in the manner shown in Fig. 2, and a spray of the usual type fixed in said chamber above the bottles being brushed covers them with water during the brushing operation.

These brushing and rinsing operations are carried out by means of the main rocker arm 71, pivoted at 72 to an upright member of the machine frame, actuated by the crank disc 73

keyed to the camshaft 1, as shown in Figs. 1 to 4 incl. As the crank disc 73 revolves with the shaft the near end of the main rocker arm 71, connected thereto by rod 74, is lowered to the position shown in Figs. 1, 2, 3.

The forward end of said main rocker arm 71 is linked with another rocker arm 75 keyed to a shaft 76 which is journaled in machine frame and extends transversely across the machine. On the opposite end of said shaft 76 another rocker arm identical with arm 75 is keyed, and in the same relative position. Both rocker arm 75 and its counterpart on the opposite side of the machine are pivoted by a connecting member to the vertically movable member 77, mounted in the vertical groove between the uprights 51, said member 77 supporting the gear box 69 with its projecting stems 50 and brushes 49. Weights on the opposite end of said rocker arms 75 counterbalance the weight of the gear box 20 and facilitate the operation of the machine.

Approximately midway its connection with the connecting member 74 and its pivot 72, the main rocker arm 71 is linked by 81 with the rocker arm 78, said latter arm being keyed to the shaft 25 79 extending transversely across the machine, journaled in the frame thereof, and having keyed on its opposite end a counterbalanced rocker arm similar to and in the same relative position as arm 78. Both of these arms 78 are pivoted at 30 their forward ends by a connecting member to a transverse unit comprising a series of vertically movable spindles 67, slidably mounted between the uprights 80. The rocker arm 78 on the side opposite that shown in Fig. 2 is counterbalanced with a weight similar to rocker arm 75.

Transverse series of vertical stems 50 project from the gear box 69, have brushes 49 secured to the ends thereof, said stems and brushes being 40 revolved by the movement of the gears in said box. Said stems 50 are partially enclosed by the sleeves 48 depending from the centering funnels above through their U-shaped supporting members, which sleeves act as guides and retaining members for the brushes in their vertical movement in and out of the bottles.

The downward movement of the crank 73 and upward movement of the main rocker arm 71 at its forward end, aided by the counterweights on 50 rocker arms 75 raises the gear box 69 and revolving brushes 49 to the position shown by Figs. 1 and 2 so that the brushes enter the bottles seated in the funnels through which the brushes are guided by the sleeves 48, and said bottles are held against upward or revolving movement by the plate 61.

The same downward movement of the crank disc 73 and near end of the main rocker arm 71 gives a reciprocating movement to the smaller 60 rocker arm 78 by means of the link 81 and, aided by the counterbalanced arm 78 on the opposite side of the machine, raises the spindles through their respective overhead centering funnels into the bottles, whereby said bottles are pushed upwardly out of their carrier and held on said spindles between the rotary brushes in the chamber 68.

The main feed pipe 82 connects to the flexible hose 47 connecting the headers 45 for the rinse jets 46 and is fitted with the valve 83 operated by the lever 84. The rod 85 connects said lever with the rocker arm 75 on the side of the machine midway its shaft 76 and its pivot to the gear box support, so that upon the upward move- 75

ment of that portion of the rocker arm the valve is opened and the water under pressure admitted to the flexible pipe 47, header 45, and rinse jets 46, the funnels 43 having previously been seated against the bottles.

As the rotary movement of the crank disc 73 actuates the near end of the rocker arm 71 upwardly, the reciprocating movements of the connected arms 75-78 hereinbefore described with 10 draws the internal rinse brushes 49 from the bottles, lowers the spindles 67 holding the bottles between the rotary brushes in chamber 68 and allows them to resume their normal position in the carriers, and closes the valve 83 preparatory to the lowering of the centering funnels and forward movement of the bottle carriers, hereinbefore described.

The catch basin 36, which receives the drippings from the bottles during their brushing and rinsing operations, may be connected with the sewer by any conventional type of outlet.

It is not to be understood from the foregoing description of my invention that I limit it to a machine with a specified number of bottle compartments in the carriers, or to any specified number of spindles 67, funnels 43, brushes 49, or rinse jets 46. These and other features of my invention may vary with the number of bottles it is desired to accommodate in the machine at one time.

Having thus described my invention, I claim:

1. In a bottle washing machine, a frame comprising side portions, a bottom portion, and end portions, said end portions extending upwardly and forming a tank, an endless bottle carrier conveyor mounted in said tank, said endless conveyor having a portion defining an incline from the rear end of said tank to the top of said frame, conveyor actuating means comprising reciprocating pawl arm means engaging the conveyor and actuated by levers, bottle brusher means mounted in said frame, means for vertically reciprocating said brusher means to and from operating position with respect to the conveyor comprising rocker arm means linked at one end thereto with counterbalance means at the opposite end thereof, bottle sprayer means comprising a vertically reciprocating supporting member mounted in said frame, supporting member reciprocating means comprising rocker arm means linked thereto and keyed on a transverse shaft mounted in said frame, a rotatable shaft transversely mounted and housed in the upper corner portion of said frame defined by the incline of said endless conveyor and remotely outside thereof, a gear wheel mounted on said shaft within the side portions of said frame, a plurality of box cams on the faces of said gear wheel, said cams being operatively connected with said pawl arm actuating levers and with said transverse shaft comprising the sprayer reciprocating means, and rotatable crank means mounted on the end of said rotatable shaft outside said frame and operatively connected with said rocker arm means comprising the brusher reciprocating means.

2. In a bottle washing machine, a frame comprising side portions, a bottom portion, and end portions, said end portions extending upwardly approximately midway the height of said frame and forming a tank, an endless conveyor mounted in said tank, said endless conveyor having a portion defining an incline from the rear end of said

tank forwardly to the top of said frame, said endless conveyor equipped with bottle carrier units extending transversely across said machine and adapted to travel with said conveyor, conveyor actuating means comprising reciprocating pawl arm means actuated by levers, bottle brusher means mounted in said frame, means for vertically reciprocating said brusher means to and from operating position with respect to the conveyor comprising rocker arm means linked thereto with counterbalance means at the opposite end thereof, bottle sprayer means comprising a vertically reciprocating supporting member mounted in said frame, supporting member reciprocating means comprising rocker arm means linked thereto and keyed on a transverse shaft mounted in said frame, a rotatable shaft transversely mounted and housed in the upper corner portion of said frame defined by the incline of said endless conveyor and remotely outside thereof, a gear wheel mounted on said shaft within the side portions of said frame, a plurality of box cams on the faces of said gear wheel, said cams being operatively connected with said pawl arm actuating levers and with said transverse shaft comprising the sprayer reciprocating means, and rotatable crank means mounted on said rotatable shaft outside said frame and operatively connected with said rocker arm means comprising the brusher reciprocating means.

3. In a bottle washing machine, a frame comprising side portions, a bottom portion, and end portions, said end portions extending upwardly approximately midway the height of said frame and forming a tank, an endless conveyor mounted in said tank, said endless conveyor having a portion defining an incline from the rear end of said tank forwardly to the top of said frame, laterally along said frame and downwardly to the entrance to said tank, said endless conveyor equipped with bottle carrier units extending transversely across said machine and adapted to travel with said conveyor, conveyor actuating means comprising reciprocating pawl arm means actuated by levers, bottle brusher means slidably mounted in the side portions of said frame, means for vertically reciprocating said brusher means to and from operating position with respect to said conveyor comprising rocker arm means linked thereto with counterbalance means at the opposite end thereof, bottle sprayer means comprising liquid jets on a vertically reciprocating supporting member slidably mounted in the side portions of said frame, supporting member reciprocating means comprising rocker arm means linked thereto and keyed on a transverse shaft journaled in said frame, a rotatable shaft transversely mounted and housed in the upper corner portion of said frame defined by the incline of said endless conveyor and remotely outside thereof, a gear wheel mounted on said shaft within the side portions of said frame, a plurality of box cams on the faces of said gear wheel, said cams being operatively connected with said pawl arm actuating levers and with said transverse shaft comprising the sprayer reciprocating means, and rotatable crank means mounted on said rotatable shaft outside said frame and operatively connected with said rocker arm means comprising the brusher reciprocating means.
